UNITED STATES PATENT OFFICE.

JOHANN HERMANN D. BLANKE, OF LE MARS, IOWA.

SIGNALING DEVICE.

1,174,810.

Specification of Letters Patent.

Patented Mar. 7, 1916.

Application filed July 25, 1914. Serial No. 853,086.

To all whom it may concern:

Be it known that I, JOHANN H. D. BLANKE, a citizen of the United States, residing at Le Mars, in the county of Plymouth and State of Iowa, have invented certain new and useful Improvements in Signaling Devices; and I do hereby declare the following to be a full, clear, and exact description of the invention, such as will enable others skilled in the art to which it appertains to make and use the same.

This invention relates to new and useful improvements in signaling devices, and has for its principal object to provide a device which is particularly adapted for use on street cars or similar vehicles.

Another object of the invention is to provide a simple and effective device which will give a signal when a vehicle is about to stop or has come to a standstill.

A further object of the invention is to provide an automatic circuit closer which is operated through centrifugal force and indicates to the user the fact that a vehicle has stopped or the speed retarded.

With these and other objects in view, the invention consists in the novel combination and arrangement of parts which will be fully set forth in the following specification and accompanying drawings, in which,

Figure 1 is a side view in elevation of a signaling device constructed in accordance with this invention and showing the same with the circuit open. Fig. 2 is a longitudinal sectional view illustrating the device with the circuit closed. Fig. 3 is a top plan view of the device. Fig. 4 is a fragmentary sectional view taken on line 4-4 of Fig. 2, and Fig. 5 is a view similar to Fig. 4 looking in the direction of the arrow.

Referring now to the drawings by characters of reference, the numeral 1 designates the base plate of the device having secured thereto the upstanding cylindrical member 2. This cylindrical member is provided at its upper extremity with the reduced cylindrical extension 3 which forms the shoulder 4, the use of which will appear as the description proceeds.

Rotatably mounted on the stem 2 is the sleeve 5 having formed at its lower end the wheel 6. The upper end of this sleeve is provided with the laterally extending arms 7 which are spaced from each other to form the slots 8.

Pivots mounted between the arms 7 as

at 9 are the arms 10 carrying at their lower terminals the reduced extensions 11 through which the pivot pin 12 is extended. An arcuate lateral extension 13 is formed on each of the arms and is provided with a plurality of apertures 14, the use of which will appear as the description proceeds. Formed laterally of the upper ends of the arms 10 are the enlargements 15 which are provided with the upstanding members 15 and 16 carrying the insulation 17, which is arranged to support the contact plate 18.

Pivots secured to the pin 12 intermediate its ends is the lever 19 carrying at its lower terminal the weight 20. The upper end of this lever is provided with a suitable aperture through which a pin 21 is arranged to extend. This pin 21 is so arranged that it projects through the apertures 14 hereinbefore referred to, and thus holds the lever 19 in adjusted position with relation to the arms 10.

A suitable disk 22 having the central aperture 23 formed therein surrounds the upstanding portion 3 of the stem 2 and said disk is provided with the transverse groove 24, which is arranged to register with the aperture 25 formed in the extension 3 to receive the pin 26, by means of which the disk 22 is held in place. A suitable annular recess 27 is formed in the under face of the disk 22 and forms the flange 28 upon which the insulating material 29 supporting the contact ring 30, is secured. A suitable longitudinal aperture 31 extends through the disk 22 near the aperture 23 and is arranged to form a passage for a suitable lubricant by which the sleeve 5 may be lubricated to permit the same to rotate freely on the stem 2.

A suitable ring 32 having the enlarged central aperture 33 formed therein, is arranged to fit the disk 22 and be supported thereon by means of the screw 33'. This ring is provided with an internal recess 34, the walls of which support the insulating material 35, by means of which the contact ring 36 is supported. This contact ring is connected to a suitable wire 37 which establishes communication between the contact ring and the signaling device designated by the numeral 38. The opposite terminal of the signaling device is connected to the wire 39, which is in turn connected to one pole of a power source 40. The opposite pole of the power source 40 is connected by

means of the wire 41 to the contact plate 30 and thus when the contact plate 18 engages both of the contact rings 30 and 36, it will be apparent that the circuit will be completed through the signaling device, and thus a warning given.

From the foregoing it will be apparent that in use when the levers 9 are in the position illustrated in Fig. 2, the signal will be given and indicate that the vehicle is at a standstill. Upon movement of the vehicle it will be apparent that power will be transmitted to the wheels 6 which will cause the sleeve to revolve, and thus swing the arms 19 outwardly into the position illustrated in Fig. 1, which will break the circuit and thus cause the signal to stop.

While in the foregoing there has been shown and described the preferred embodiment of this invention, it is to be understood that such changes may be made in the combination and arrangement of parts as will fall within the spirit and scope of the invention as defined in the appended claims.

Having thus described my invention, I claim:

1. A device of the character described comprising a base plate, a central upstanding cylindrical member formed on the base plate, a sleeve rotatably mounted on the central cylindrical member, a drive wheel on the sleeve, arms extending laterally from the upper terminal of the sleeve, arms pivotally secured to the arms and arranged to swing outwardly, contact plates carried by the pivoted arms, a ring supported on the

upper end of the upward extension of the base plate, a ring supported on the upper end of the cylindrical extension on the base plate, a ring surrounding the disk, and a pair of contact rings carried by the disk and rings and arranged to coöperate with the contact plates carried by the arms and completing an electrical circuit.

2. A device of the character described comprising a base plate, an upstanding cylindrical extension formed centrally of the base plate, a reduced cylindrical extension at the free terminal of the upstanding cylindrical extension, a sleeve rotatably mounted on the upstanding extension, a drive wheel carried by the sleeve, a pair of arms extending laterally from the sleeve, a pair of pivoted arms secured to the laterally extending arms, weights carried by the pivoted arms, said pivoted arms being arranged to swing outwardly when the sleeve is rotated, contact plates carried by the pivoted arms at their upper terminals, a disk mounted on the reduced extension on the cylindrical portion, a ring surrounding the disk and arranged to be secured thereto, and a pair of contact rings adapted to coöperate with the contact plates to close a circuit through an electrical signaling device.

In testimony whereof I affix my signature in presence of two witnesses.

JOHANN HERMANN D. BLANKE.
